VACUUM TUBE

Ilia E. Mouromtseff, Wilkinsburg, Pa., assignor to
Westinghouse Electric & Manufacturing Company,
a corporation of Pennsylvania

Application April 11, 1929, Serial No. 354,290

1 Claim. (Cl. 250—27.5)

My invention relates to vacuum tubes and is particularly applicable to the high-power tubes used in transmitting stations and especially to tubes in which it is proposed to develop as high power as possible at as short wave length as possible.

It has been found desirable, in building high-power tubes, to adopt long electrodes. With such electrodes parasitic oscillations of very high frequency occasionally arise which are accompanied

by the production of standing waves on the grid. This has the disadvantage that a certain portion of the energy is wasted. It has the further disadvantage that very high potentials may be developed at points in the structure where the parts of glass, quartz, or other insulating material are exposed to the potential-gradient. The insulation is thereby subjected to heavy stresses. Punctures, fusion or fracture may then be occasioned.

It is an object of my invention to provide a means whereby the production of standing waves upon the grid will be prevented.

It is a further object of my invention to provide for damping the frequencies which tend to produce such waves.

It is a further object of my invention to provide a connection uniting the two ends of the grid structure, distinct from the connections between the ends of the grid formed by the usual parts of the grid structure.

It is a further object of my invention to provide impedance devices which will prevent the flow of high-frequency current around the circuit comprising the usual grid structure and the additional connection.

Other objects of my invention and details of the construction will be apparent from the following description and the accompanying drawing, in which,

Figure 1 is a longitudinal section of one form of vacuum tube to which my invention is applied.

Fig. 2 is a longitudinal section of a tube of modified structure, and

Fig. 3 is a perspective view of a damping device which may be employed in a vacuum tube of either form.

In the vacuum tube illustrated in Fig. 1, the anode is a metallic cylinder 1, sealed, at each end, into glass end-portions 2 and 3. The cathode 4 is mounted in a press in the glass end 2 in a usual way.

The grid is mounted upon a sleeve 5, clasping the press in the other glass end 3. Standards 6 are welded, or otherwise secured, to the sleeve 5.

For the sake of clearness, only two such standards

are shown in the drawing but any convenient number may be employed and, ordinarily, four or six standards are provided. At their upper ends, the standards 6 are welded, or otherwise secured, to a metal ring 7 which surrounds the press in the glass end 2 but is spaced away from it. The ring 7 is preferably supported by glass supports 8 which extend from it to the hollow part of the press.

The standards 6 support the usual metal open-work constituting the grid proper and, with the rings 5 and 7, constitute the usual grid structure. In the tube illustrated, the open-work is formed by winding a fine wire 10 upon the standards, securing it thereto, at many points if not at every whorl, preferably by welding. If preferred, the grid structure may take any of the forms disclosed in my copending application, Serial No. 344,772 filed March 6, 1929 for Vacuum tubes.

The lead-in wire 11 for the grid extends through the press of the glass end 3 in the usual way. It is illustrated as branched and is connected to each of a plurality of the standards 6. The conductor conveying the grid current is illustrated at 12. It is branched, one branch being connected to the lead-in wire 11 and the other branch, including a resistor 13 and a condenser 14, extending through a seal 15 in the glass end 2 to connect the conductor 12 to the end of the grid structure.

The connection, as illustrated, extends to the ring 7, but any convenient point near this end of the grid structure may be chosen for the terminus of this branch. The resistor 13 may, if desired, be replaced by a small concentrated inductance, for example, one or two turns, and the condenser 14 may be omitted, if desired.

In the form illustrated in Fig. 2, the vacuum tube is provided with but one glass end 20. The anode is a metallic thimble 21, sealed into the glass end 20, the usual connections for the cathode 22 extend through the press in the glass end 20.

The upper end of the cathode is supported by a quartz rod 23 which, in turn, is supported by the standards 24 which constitute part of the grid structure. The upper end of the quartz rod 23 is held stationary by means of a disk 25 extending to the wall of the tube. The rod is secured to the standards 24 in any desired manner.

For illustration, the rod is shown as fused, at 26, to a cross connection 27 uniting two of the standards 24. Although only two standards are illustrated, it is intended that any convenient

number of standards shall be used, and ordinarily there will be four.

The standards are secured, by welds or any other suitable joints, to a ring 28 clasping a glass sleeve 29 which extends upward from the bottom 5 of the press.

The lead-in wire for the grid is shown at 31 as extending through a seal 32 in the side of the glass end and connected, by welding or any other 10 suitable joint, to the ring 28, which is part of the grid structure.

A connection 33 extends from the upper end of the standards 24 to a point near the ring 28 and is there connected, by soldering or other good 15 electrical connection, to one of the standards 24. This conductor includes a resistor 34, preferably near one end thereof. If desired, a small inductance, such as one or two turns, may be inserted in the conductor 33 instead of the resistor. 20

At its upper end, the conductor 33 is shown closely adjacent to the quartz rod 23 but this is not an essential location of the conductor end. The quartz rod 23 extends a considerable distance from the point 26, at which the standards 25 24 are mechanically connected with it, to the top 35 of the cathode, at which point it is connected to the cathode to support the same.

In any power tube having an elongated grid structure, it is the usual practice to provide considerable unoccupied length of the standards at each end of the metal open-work. This has been illustrated in Fig. 2, where the standards 24 extend considerably above and below the fine wire 36 which constitutes the open-work, as illustrated. 30

One way of providing the damping which may be employed as a substitute for or, in cooperation with, the impedance 34, is illustrated in Fig. 3. This device consists of a sleeve 49 which may be threaded upon the standard 24 during the manufacture of the tube. One of these devices may be located upon each standard above and another below the metal open-work, or a smaller number of such devices may be used if the damping to be effected thereby is small. 45

The sleeve 49 is equipped with a plurality of fins 41. The fins, or preferably, the whole device, will be of magnetic material.

In the operation of my invention; when the power tube is generating oscillations, any frequency capable of producing standing waves upon the grid structure is rendered ineffective. In Fig. 50 1, this is done by supplying grid potential to both ends of the grid structure. The grid current arrives through the conductor 12 and is supplied to one end of the grid through the lead-in wire 11 and to the other end of the grid through the resistor 13 and the condenser 14. The presence 55

of the condenser prevents any direct-current component of the grid current from entering the tube through the seal 15. The total current carried by the seal 15 is, therefore, small and a less elaborate lead-in structure is needed than that 5 shown at 11.

The frequencies most likely to produce standing waves upon the grid are multiples of the fundamental frequency of the grid structure to electrical oscillations. Such frequencies, if present, 10 will tend to generate a current of this frequency in the circuit comprising the grid structure and the connection through the condenser 14 and the resistor 13. Such currents will be rapidly damped by the resistor 13. This will prevent parasitic 15 frequencies corresponding to such standing waves from occurring but will not interfere with the basic frequency of the circuit in which the tube is situated, which ordinarily differs widely from 20 the parasitic frequency.

In Fig. 2, the connection from the upper part 21 of the grid structure to a point in it near the ring 28 completes a circuit in which current would flow if the frequency tending to produce standing waves were present, but oscillation at 25 this frequency is prevented by the damping action of the resistor 34 or by the impedance of the self-inductance located at this point. In this way, the frequency corresponding to standing 30 waves on the grid cannot be one of the natural periods of the system, and standing waves will, therefore, not be produced.

If the devices illustrated in Fig. 3 are located on the standards, in the grid structure of either 35 Fig. 1 or Fig. 2, the high-frequency currents will induce eddy currents in the magnetic material which will thus act as a damping means. The production of standing waves will thus be prevented in the same way as by the other damping means described. 40

Although I have illustrated and described only a few modifications of my invention, many other variations will be readily apparent to those skilled in the art. The absence of any specific description thereof is not intended as a limitation. No 45 limitation is intended except that required by the prior art or expressed in the accompanying claim.

I claim as my invention:

A vacuum tube including an anode, a cathode, 50 and a grid structure, connecting means extending from the ends of said grid structure, an impedance and a capacity, said impedance and capacity, only, forming a closed circuit with said grid structure and connecting means, and a grid input connection to said closed circuit.

ILIA E. MOUROMTSEFF.
